CHANUKAH DISPLAY ORNAMENT

Sara Rae Naimon, Milwaukee, Wis.

Application February 27, 1956, Serial No. 40,344

Term of patent 14 years

(Cl. D29—1)

Fig. 1.

Fig. 2

Fig. 3.

Fig. 4.

Fig. 5.

The dominant features of the design reside in the portion shown in full lines in the drawing.

I claim:

The ornamental design for a Chanukah display ornament, as shown and described.
